UNITED STATES PATENT OFFICE.

CHARLES R. KAISER, OF ROCKPORT, INDIANA.

DESIGN FOR A CHAIR SEAT AND BACK.

SPECIFICATION forming part of Design No. 31,313, dated August 1, 1899.

Application filed July 5, 1899. Serial No. 722,898. Term of patent 7 years.

To all whom it may concern:

Be it known that I, CHARLES R. KAISER, a citizen of the United States, residing at Rockport, in the county of Spencer and State of Indiana, have invented and produced a new and original Design for Chair Seats and Backs; and I do declare the following to be a full, clear, and exact description of the same, reference being had to the accompanying drawing, forming a part thereof.

The figure is a perspective view of a chair seat and back, showing my new design.

Referring by letter to said drawing, A is the chair-seat; B, the back, which is made up of turned side uprights *a*, bottom and top cross-bars *b* *c*, and an intermediate cross-bar *d*, and C are the arms.

As shown in the drawing, the leading and material feature of my design is the chair seat and back.

The intermediate cross-bar *d* of the back B is provided at its middle with a circular enlargement *e*, upon which, within a circular series of small circles *f*, is arranged a portrait of Admiral Dewey. A view of a man-of-war is placed on the upper cross-bar *c* of back B and is disposed within a margin of black dots *g*, representing cannon-balls, and above a space *h*, designed for the reception of a suitable inscription, while a superposed portion *i*

of the seat A bears a view of the wrecked battle-ship Maine.

The features mentioned, together with two United States flags on the cross-bar *d* and two United States shields and a chain on the cross-bar *b*, are intended to be embossed or otherwise produced in relief on the chair seat and back.

Between the enlarged circular portion *e* of the intermediate cross-bar *d* and the upper and lower cross-bars *b* *c*, respectively, are interposed turned spindles *j*.

As illustrated, the arms C of the chair are shaped like cannon and are supported by United States shields *k* and turned spindles *l*, interposed between them and the seat A. The said shields *k* are embossed on opposite sides and are each arranged upon a ball *k'* and surmounted by three balls *m*, arranged after the manner shown.

Having thus described my invention, what I claim is—

The design for a chair seat and back, as herein shown and described.

In testimony whereof I affix my signature in presence of two witnesses.

CHARLES R. KAISER.
